US0D1000387S

(12) **United States Design Patent** (10) Patent No.: **US D1,000,387 S**
(45) Date of Patent: ** Oct. 3, 2023

(54) **DATA PROCESSING EQUIPMENT**

(71) Applicant: **EPEC OY**, Seinäjoki (FI)

(72) Inventor: **Tuomo Yli-Taipalus**, Seinäjoki (FI)

(73) Assignee: **EPEC OY**, Seinäjoki (FI)

(**) Term: **15 Years**

(21) Appl. No.: **29/733,403**

(22) Filed: **May 1, 2020**

(30) **Foreign Application Priority Data**

Nov. 4, 2019 (EM) 007182647-0001

(51) **LOC (14) Cl.** **13-02**

(57) **CLAIM**

The ornamental design for data processing equipment, as shown and described.

DESCRIPTION

FIG. 1 is a front perspective view of data processing equipment in accordance with my new design;

FIG. 2 is a front elevation view thereof;

FIG. 3 is a rear perspective view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the data processing equipment that form no part of the claim designed.

1 Claim, 8 Drawing Sheets
